(57) **CLAIM**

The ornamental design for a “multi-use insert for a single container,” as shown and described.

DESCRIPTION

The claimed “multi-use insert for a single container” may be used in conjunction with the packing, storage and shipping of a fragile container such as a glass bottle.

FIG. 1 is a perspective view of the top, front and right sides of a multi-use insert for a single container;

FIG. 2 is a front elevation view of the multi-use insert for a single container;

FIG. 3 is a right side elevation view of the multi-use insert for a single container;

FIG. 4 is a rear elevation view of the multi-use insert for a single container;

FIG. 5 is a left side elevation view of the multi-use insert for a single container;

FIG. 6 is a top plan view of the multi-use insert for a single container;

FIG. 7 is a bottom plan view of the multi-use insert for a single container;

FIG. 8 is a cross-sectional view of the multi-use insert for a single container taken along line 8—8 of the FIG. 6 view; and,

FIG. 9 is a perspective view of a multi-use insert for a single container in use.

The broken-lines of FIG. 9 depict elements of the environment and additional inserts. These broken line features are depicted for illustrative purposes only, and form no part of the claimed design.
